CLAIM

We claim the ornamental design for a console for vehicle, as shown and described.

DESCRIPTION

FIG. 1 is a front perspective view of a console for vehicle showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof;

FIG. 9 is an enlarged view of the portion 9 encircled in FIG. 1;

FIG. 10 is an enlarged view of the portion 10 encircled in FIG. 8;

FIG. 11 is a front perspective view thereof showing a first example state of use;

FIG. 12 is another front perspective view thereof showing a second example state of use;

FIG. 13 is another front perspective view thereof showing a third example state of use; and,

FIG. 14 is an enlarged view of the portion 14 encircled in FIG. 13.

The evenly-dashed broken lines in the figures depict environmental subject matter and form no part of the claimed design.

The dot dash broken lines in the figures represent boundaries of the claimed design and form no part thereof.

The dot-dot-dash broken lines encircling portions of the claimed design that are illustrated in enlargements form no part of the claimed design.
